CAR COUPLER

Burns D. Lockwood, New Castle, Pa., assignor, by
mesne assignments, to Koppel Industrial Car
and Equipment Company, McKees Rocks, Pa., a
corporation of Pennsylvania

Application May 17, 1929, Serial No. 363,755

2 Claims. (Cl. 213—86)

My invention lies in the provision of a coupler for cars of the type which employ link and pin means for joining the cars together.

An object of my invention is to provide such a coupler in which the number of parts is reduced to a minimum and so secured together that they may not be easily separated and lost or stolen.

Another object of my invention is to provide a coupler which may be applied to both ends of a car and which may be operated by the trainman without excessive risk of personal injury.

Another object of my invention is to provide a coupler in which the coupling link, when inactive, may be retracted into a position to prevent possible injury thereto when using the link of the opposing coupler on the other car to couple the cars together, and to avoid its interference with the coupling link which is being used, and which may be easily moved and automatically secured into retracted position.

Referring now to the drawing, Fig. 1 shows the position of the couplers when moved together in coupling position and the inactive link is moved into retracted position; Fig. 2 shows the couplers of two connected cars when the buffering springs of the two cars are fully compressed and the resultant position of the active and inactive coupling links.

Referring now to the drawing where like reference characters refer to like parts, reference character 1 indicates a coupler comprising a stationary portion 2 secured to the car body and a draw head 3 to which is secured the draw bar 4. The portion of the draw bar which is secured to the car body and to the buffering springs which transmit the buffering shocks away from the coupler and car body and the method of attaching 40 same to the car body form no part of my present invention, and for that reason have been omitted. In this connection it will suffice to say that the member 5 is moved along the draw bar 4 until the required tension in the draft 45 springs is obtained and the pin 6 is inserted through the members 4 and 5, locking them into position. In the present embodiment of the invention it is necessary to fully compress the draft springs, as shown in Fig. 2, until the opening 50 18 in the member 2 coincides with the openings 7 in the member 3 after which the pin 6 may be readily inserted and fastened into position. A portion of the draft springs is shown in cross section at 8 and is shown encircling the 55 member 3 and abutting against the shoulder 9

thereof. However, it is to be understood that the details of the draw bar and buffer spring need not be as shown in the drawing and can be modified to suit the particular needs of the car on which the coupler is used.

The essential elements of my invention comprise a draw head 3 having a coupling pin 10 projecting through openings 11 in the forward portion of the draw head to maintain a coupling link 12 within the draw head the upper rearward portion of the draw head having a recess 13 into which the link 12 may be retracted when not in use. To the rear of the coupling pin and extending transversely of the draw head in a position to engage with the coupling link is a guide member 14 which engages with the link as it is moved inwardly and guides the link upward and into the recess 13. Pivotedly mounted on the draw head is a cover 15 which extends over the end of the recess 13 and has a latch member 16 pivotally attached thereto. The latch member 16 extends downward through the cover into the recess 13 and is lifted by the link moving into retracted position and as the end of the link moves beyond the end 17 of the latch, the latch falls downward by reason of its own weight and automatically engages with the link locking it into retracted position. The cover member 15 serves the purpose of preventing debris from entering the recess 13 and preventing the link 12 from moving freely in the recess.

The link member 12 has the rearward portion thereof deflected upward from the plane of the major portion of its length so as to facilitate the entrance of the link into the recess 13 and to prevent binding between the link 12, draw head 3 and the portion 2 of the coupler when the draft springs are fully compressed by the cars moving towards each other as is shown in Fig. 2 of the drawing.

The coupling pin 10 is movably mounted in the openings 11 at the forward portion of the draw head 3 and performs the double function of engaging with the link of the adjacent car to which its respective car is being coupled and also preventing the removal of the link 12 from the draw head. This coupling pin comprises the handle portion 19 and the link engaging portion 20 and has at one end of the portion 20 an enlarged portion 21 which is small enough to pass between the sides of the link member 12 but is too large to pass through the opening 11—A at the top of the coupler, and for this reason cannot be readily lost or stolen from the draw head. Mounted on the portion 20 of the pin is a washer member 22 which

has an inside diameter slightly larger than the diameter of the portion 20 so as to be freely movable thereon and has an outside diameter larger than the opening between the sides of the link member 12 so that once the link member of the individual coupler is engaged by its respective coupling pin the coupling link 12 cannot be readily lost or stolen. The coupling pin 10, as was stated, consists of the handle portion 19 and the portion 20 which is engaged by the handle portion and in assembling the individual coupler the portion 20 is removed from the handle and the end to be engaged by the handle is inserted into the lower portion of the draw head through the opening 11, 15 through the washer 22, link 12 and the upper opening 11—A of the draw head. The handle member 19 is again mounted on the portion 20 and the pin member 23 inserted through the members 19 and 20 locking them into engagement with each other.

When it is proposed to couple two cars together as shown in Fig. 1, the following actions would take place:—Assuming that the link 12 of both couplers is in extended position, the link of one 25 of the couplers such as that shown on the left side of Fig. 1 would be moved into retracted position. This would be done by moving the link inwardly of the draw head where it strikes the portion 14 of the draw head and is deflected upward until the inner end of the link engaged with the portion 24 of the draw head which is suitably formed so as to guide the link upward and yet prevent binding as the link engages with the portion 25 of the stationary portion 2 of the coupler. The continued movement of the link causes it to pass into the recess 13 where it is automatically engaged by the latch member 16 when in fully retracted position as shown. As the two cars now approach each other, the coupling pin 10 of the coupler at 30 the left side of Fig. 1 is raised until the portion 21 of the pin engages with the washer 22 forcing the washer into engagement with the link 12 and lifting the link out of the way of the entering link of the approaching coupler after which the pin is dropped through the entering link 12 and the opening 11 in the lower portion of the draw head, 35 coupling the cars together.

The position of the respective couplers and coupling link when the cars are in motion and the couplers are separated the length of the link 12 has not been shown since there would not be any change in the relative position of any of the parts of the two couplers with the exception of the separation of the couplers to an amount equal to the length of the connecting link. However, when the cars are buffing one against the other and the buffing springs of the two cars are being com-

pressed there is a change in the relative position of the parts of the various couplers and their extreme position is shown by Fig. 2 in which the buffer springs of both cars have been fully compressed and the stationary portion 2 of the coupler has moved forward along the draw head into its extreme forward position as shown. As the portion 25 of the member 2 moves along the draw head, the retracted link member 12 is lifted causing the upper end of the link to lift the cover member 15 and consequently move the link member into engagement with the portion 24 of the draw head. This upward movement of the cover member frees the latch member from the link and permits the link to assume the position shown on the left side of Fig. 2. The active link coupling the two cars together may proportion itself between the two cars, or may shift to one side until one end of the link is in engagement with one of the coupling pins and the other end of the link 80 would strike with the guide portion 14 of the draw head and move up into the recess 13 and prevent any binding between the links themselves or the link and draw head. After the buffing shock has been dissipated and the member 2 of the coupler 85 moves to its normal position as indicated by Fig. 1, the links would move downward by reason of their own weight and the latch member 16 would again automatically engage with the retracted link and retain it in retracted position.

Having thus described the invention what I claim as new and desire to secure by Letters Patent is:

1. In a car coupler in combination a body portion, a movable head, a coupling link within said head and a coupling pin movably mounted within said head and constantly held within said link, an upwardly deflected end portion on said link disposed inwardly of said pin and an opening in the rear of said head for receiving said deflected end portion of the link when the link is moved to retracted position, and a latch mounted upon said head for holding said link in retracted position, said latch so holding said link as to permit limited movement of the link in retracted position without accidental separation of the link and latch.
2. In a car coupler, in combination, a drawhead, a coupling link within said head, an opening in said head for reception of the link in retracted position, a coupling pin mounted in said head, within said link and movable to admit an entering link of an adjacent coupler, said pin preventing separation of the link and head when the link is in coupling or retracted position, and means within said head for guiding the movements of the link about the pin.
